UNITED STATES PATENT OFFICE.

GEORGE EDWARD MOORE, OF MUSKEGON, MICHIGAN, ASSIGNOR TO MANNING, MAXWELL & MOORE, INC., OF MUSKEGON, MICHIGAN.

HOIST.

Application filed April 29, 1926. Serial No. 105,495.

The objects of the invention are:

First, to provide an improved hoist which is well adapted for the hoisting of locomotives to facilitate the removal and replacing of wheels on trucks or other repair work.

Second, to provide an improved hoist adapted for the hoisting of locomotives or the like which does not require pits or special foundations and occupies but comparatively little overhead space.

Third, to provide an improved hoisting apparatus of the class described which is very powerful and at the same time is compact and simple in structure.

Objects pertaining to details and economies of my invention will definitely appear from the detailed description to follow. The invention is clearly defined and pointed out in the claims.

A structure embodying the features of my invention is clearly illustrated in the accompanying drawing forming a part of this application, in which:

Fig. 1 is a side elevation of my improved hoisting apparatus, a locomotive being conventionally indicated by dotted lines in position to be hoisted.

Fig. 2 is a front elevation of one of the hoisting units.

Fig. 3 is a detail view partially in vertical section on a line corresponding to line 3-3 of Figs. 2, 6, 7 and 8.

Fig. 4 is a fragmentary plan view showing driving connections from the motor to the driving shaft.

Fig. 5 is a fragmentary view on a line corresponding to line 5-5 of Fig. 1 showing details of one of the trucks.

Fig. 6 is a detail view partially in section on a line corresponding to line 6-6 of Figs. 1, 3, 7 and 8.

Fig. 7 is a horizontal section on a line corresponding to line 7-7 of Fig. 3.

Fig. 8 is a horizontal section on a line corresponding to line 8-8 of Figs. 3 and 6.

Fig. 9 is a vertical section on a line corresponding to line 9-9 of Fig. 5 showing details of the truck with the spring supported truck body in unloaded position.

Fig. 10 is a fragmentary view partially

in section on a line corresponding to line 10-10 of Fig. 5 with the truck body in its loaded position.

Referring to the drawing, 1 represents the floor of a shop having tracks 2 therein adapted to carry a locomotive shown conventionally in Fig. 1. In hoisting a locomotive a pair of units is employed but as these are duplicates a description of one will suffice.

Each unit is carried by a pair of trucks adapted to travel on the track 2', the trucks comprising body portions designated generally by the numerals 3 having columns 65 designated generally by the numerals 4 mounted thereon.

The body portions of the trucks are supported when not under load by means of the coiled springs 5 arranged in the pockets 5' 70 in the bed members of the truck, which are carried by the axles 7 of the wheels 8. One wheel of each truck is provided with a ratchet wheel 9 which is driven through a lever 10 having a pawl 13 coacting with the 75 ratchet wheel, the lever being mounted on the end of the axle. The springs 5 are of such strength as to carry the hoisting apparatus with the truck body portions clearing the track. However, when subjected 80 to substantial load the springs collapse allowing the truck bodies to rest upon the floor or track thereby relieving the wheels of the load and preventing movement of the hoisting units.

The columns 4 are made up in the structure illustrated of a pair of oppositely disposed channel irons 14 connected by side plates 15 providing hollow columns. Oppositely disposed ways 16 are arranged in the 90 channels of the members 14 and uprights designated generally by the numerals 17 are telescopingly mounted on the columns, these uprights comprising the inwardly facing channel members 18 with the connecting 95 side plates 19. Slides 20 on the uprights coact with these ways 16 so that the uprights move freely on the columns and at the same time are guided in their movement.

The uprights are connected at their upper ends by means of the cross members desig-

nated generally by the numeral 21. This cross member in the embodiment illustrated consists of the vertical plates 22 with outwardly facing angle iron members 23 at the top and bottom thereof and a top plate 24 forming in combination a downwardly facing channel beam.

The side members or plates 22 are provided with a series of holes 25 adapted to receive the supporting pins 26 of the shackles 27 from which the sling bar 28 is suspended by means of the links 29. Slings may be attached to the shackles but the slings illustrated are very satisfactory for use in hoisting locomotives, one unit being arranged so that the sling bar engages under the smoke box and the other under the firebox as is illustrated in Fig. 1.

The hoisting screws 30 are rotatably mounted in head members 31 which are affixed in the upper ends of hoist uprights, bearings 32 being shouldered at 33 to rest on shoulders 34 provided in these head members. The bearings are provided with bushings 35 in the embodiment illustrated.

The bearings 32 are provided with opposed recesses 36 to receive the locking bars 37 arranged through the head members to engage these recesses 36. Thrust bearings 38 designated generally by the numerals 38 are disposed between the thrust collar 39 and the bearings 32.

The upper bearing member 40 has an outer conical surface 41 coacting with the conical thrust ring 42 so that the thrust of the screw is effectively centered.

The screws are supported in the columns by means of the stirrups 43 having external shoulders 44 resting on the ends of the columns. These stirrup members are internally shouldered at 45 to support the beveled thrust members 46. Nuts 47 are arranged in supporting sleeves 48 which have beveled shoulders 49 engaging the beveled supporting rings 46 to permit the alining of the nuts in their supporting sleeves.

The supporting sleeves have lugs 50 engaging the slots 51 in the stirrup to prevent rotation of the supporting sleeves, the nuts being secured within the sleeves. Tubular housings 52 depend from these supporting sleeves, these housings being closed at their lower ends so that they serve as lubricant retainers permitting the effective lubrication of the nut and screw.

In the embodiment illustrated the uprights and cross members are braced by the braces 53. At their upper ends the screws are provided with beveled gears 54 meshing with the gears 55 on the driving shaft 56. This shaft is connected to the motor 57 by a train of gears indicated at 58. As the details of this train of gears forms no part of this invention it is not further described herein.

I preferably provide a platform 59 at the side of the cross member, the motor being accessible from the platform.

A ladder comprising risers 60 and rungs 61 mounted on one of each pair of uprights, a section 62 being mounted on the truck and having a slide 63 engaging the risers 60 so that an extension is had when the uprights are elevated.

My improved hoisting apparatus is powerful and at the same time is relatively compact in structure and durable. I have especially designed my improvements as embodied for locomotive hoists, although it will be understood that they are adapted for other uses, especially where heavy loads are to be lifted.

I have not attempted to illustrate or describe various modifications and adaptations which I contemplate as I believe the disclosure made will enable those skilled in the art to embody or adapt my improvements as may be desired.

Having thus described my invention what I claim as new and desire to secure by Letters Patent is:

1. In a hoisting apparatus, the combination of columns provided with opposed vertical ways, uprights telescopingly mounted on said columns and provided with slides coacting with said ways, a cross member connecting the upper ends of said uprights, hoisting screws, head members on the upper ends of said uprights in which said screws are rotatably mounted, thrust bearings for said screws coacting with said head members, said screws being provided with beveled gears on their upper ends, a driving shaft provided with gears coacting with said gears on said screws, internally shouldered stirrup members mounted on said uprights, conical thrust members arranged on said stirrup member shoulders, threaded support members coacting with said screws and provided with supporting sleeves having conical shoulders coacting with said thrust members, and a sling on said cross member.

2. In a hoisting apparatus, the combination of a column provided with opposed vertical ways, an upright telescopingly mounted on said column and provided with slides coacting with said ways, a hoisting screw, a head member on the upper end of said upright in which said screw is rotatably mounted, a thrust bearing for said screw coacting with said head member, means for driving said screw, an internally shouldered stirrup member mounted on said upright, a conical thrust member arranged on said stirrup member shoulder, and a threaded support member coacting with said screw and provided with a supporting sleeve having a conical shoulder coacting with said thrust member.

3. In a hoisting apparatus, the combina-

tion of a column, an upright telescopingly mounted on said column, a hoisting screw rotatably mounted on said upright, means for driving said screw, an internally shouldered stirrup member mounted on said upright, a conical thrust member arranged on said stirrup member shoulder, a threaded support member coacting with said screw and provided with a supporting sleeve having a conical shoulder coacting with said thrust member, and a tubular screw housing depending from said sleeve providing a lubricant retainer.

4. In a hoisting apparatus, the combination of a column, an upright telescopingly mounted on said column, a hoisting screw rotatably mounted on said upright, means for driving said screw, an internally shouldered stirrup member mounted on said upright, a conical thrust member arranged on said stirrup member shoulder, and a threaded support member coacting with said screw and provided with a supporting sleeve having a conical shoulder coacting with said thrust member.

5. In a hoisting apparatus, the combination of a column provided with opposed vertical ways, an upright telescopingly mounted on said column and provided with slides coacting with said ways, a hoisting screw, a head member on the upper end of said upright in which said screw is rotatably mounted, a thrust bearing for said screw coacting with said head member, means for driving said screw, a stirrup member mounted on said upright and provided with a conical thrust member, and a threaded support member coacting with said screw and provided with a conical shoulder coacting with said thrust member.

6. In a hoisting apparatus, the combination of a column provided with opposed vertical ways, an upright telescopingly mounted on said column and provided with slides coacting with said ways, a hoisting screw rotatably mounted on said upright, means for driving said screw, a stirrup member mounted on said upright and provided with a conical thrust member, and a threaded support member coacting with said screw and provided with a conical shoulder coacting with said thrust member.

7. In a hoisting apparatus, the combination of columns provided with opposed vertical ways, uprights telescopingly mounted on said columns and provided with slides coacting with said ways, a cross member connecting the upper ends of said uprights, hoisting screws rotatably mounted at the upper ends of said uprights, a driving shaft provided with gears coacting with said gears on said screws, internally shouldered stirrup members mounted on said uprights, conical thrust members arranged on said stirrup member shoulders, threaded support

members for said screws provided with supporting sleeves having conical shoulders coacting with said thrust members, tubular screw housings depending from said sleeves providing a lubricant retainer, and a sling 70 on said cross member.

8. In a hoisting apparatus, the combination of columns provided with opposed vertical ways, uprights telescopingly mounted on said columns and provided with slides 75 coacting with said ways, a cross member connecting the upper ends of said uprights, hoisting screws rotatably mounted at the upper ends of said uprights, a driving shaft provided with gears coacting with said 80 gears on said screws, threaded support members for said screws carried by said columns, and a sling on said cross member.

9. In a hoisting apparatus, the combination of a pair of columns, uprights telescopingly mounted on said columns, a cross member mounted on the upper ends of said uprights and provided with sling connections, hoisting screws rotatably mounted on said uprights, threaded screw supporting members, supporting stirrups for said threaded supporting members carried by said columns, said nuts being mounted on said stirrups to permit the alining of the parts, and means for simultaneously driving said screws carried by said uprights. 95

10. In a hoisting apparatus, the combination of a pair of trucks, columns on said trucks provided with opposed vertical ways, uprights telescopingly mounted on said 100 columns and provided with slides coacting with said ways, a cross member connecting the upper ends of said uprights, hoisting screws rotatably mounted on said uprights, threaded supports for said screws mounted 105 on said columns, and means for driving said screws.

11. In a hoisting apparatus, the combination of a pair of columns, uprights telescopingly mounted on said columns, a cross member mounted on the upper ends of said uprights and provided with sling connections, hoisting screws rotatably mounted on 110 said uprights, threaded screw supporting members on said columns, and means for simultaneously driving said screws carried by said uprights. 115

12. In a hoisting apparatus, the combination of a pair of columns, uprights telescopingly mounted on said columns, said columns and uprights having coacting slidably engaging guide means for said uprights, a cross member connecting the upper ends of said uprights, and hoisting screws operatively associated with said uprights and columns. 120

13. In a hoisting apparatus, the combination of rails disposed with their tops flush with the surface of the rail bed, trucks comprising bed members provided with axles 130

and wheels traveling on said rails, said bed members having pairs of vertical spring pockets disposed at the sides of the wheels, truck bodies resting on said springs and provided with side members slidably embracing said truck bed members, said body being adapted to rest upon the rails and their bed when the springs are compressed, columns mounted on said bodies, uprights 10 telescopingly mounted on said columns, a cross member connecting the upper ends of said uprights, a sling carried by said cross member, and hoisting means carried by said columns and operatively associated with said uprights.

14. In a hoisting apparatus, the combination of rails disposed with their tops flush with the surface of the rail bed, trucks comprising bed members provided with 20 axles and wheels traveling on said rails, said bed members having pairs of vertical spring pockets disposed at the sides of the wheels, truck bodies resting on said springs and provided with side members slidably embracing said truck bed members, said body being adapted to rest upon the rails and their bed when the springs are compressed, and hoisting means carried by said truck body.

15. In a hoisting apparatus, the combina-

tion of rails, trucks comprising bed members provided with axles and wheels traveling on said rails, said bed members having vertical spring pockets, truck bodies resting on said springs and slidably embracing 35 said truck bed members, said body being adapted to rest upon the rails when the springs are compressed, columns mounted on said bodies, uprights telescopingly mounted on said columns, a cross member connecting 40 the upper ends of said uprights, a sling carried by said cross member, and hoisting means carried by said columns and operatively associated with said uprights.

16. In a hoisting apparatus, the combination of rails, trucks comprising bed members provided with axles and wheels traveling on said rails, said bed members having vertical spring pockets, truck bodies resting on said springs and slidably embracing 45 said truck bed members, and hoisting means carried by said trucks, said body member being adapted to rest upon said rails when the springs are compressed, the springs being of such strength as to support the body 50 out of contact with the rails when the hoisting means is not under load.

In witness whereof I have hereunto set my hand.

GEORGE EDWARD MOORE.
